A. W. ROSEN

ELECTRICAL SWITCH

Filed Jan. 27, 1922

INVENTOR
Abraham W. Rosen

John M. Rosen
ATTORNEY

UNITED STATES PATENT OFFICE.

ABRAHAM W. ROSEN, OF NEW YORK, N. Y.

ELECTRICAL SWITCH.

Application filed January 27, 1922. Serial No. 532,147.

To all whom it may concern:

Be it known that I, ABRAHAM W. ROSEN, a citizen of the United States, residing at New York city, in the county of New York and State of New York, have invented certain new and useful Improvements in Electrical Switches, of which the following is a specification.

My invention relates to improvements in electrical switches, particularly of the type employed for controlling the illuminated stop signals carried at the rear of automobiles.

The principal object of the invention is to provide a compact, simply constructed, well insulated switch, which may be produced at low cost and which is thoroughly reliable in operation.

The invention consists of the structural features and combinations hereinafter described and claimed, and illustrated in the accompanying drawing, in which Fig. 1 is a plan view of the improved switch; Fig. 2 is a side elevational view; Fig. 3 is a view similar to Fig. 1 with the switch cover removed; Fig. 4 is a longitudinal sectional view on the line 4—4 of Fig. 1; and Fig. 5 is a transverse sectional view on the line 5—5 of Fig. 1.

Referring to the drawing by reference characters, 10 denotes the base of the switch, preferably of metal, which has connected thereto or formed integrally therewith the oppositely disposed lugs or standards 11 and 12. Perforated lateral extensions 13 of the base 10 provide means by which the switch may be secured in desired position. Held to the base 10 by any suitable means, such as rivets 14, are double layers of insulating material 15 and 16. The insulating material stops short of the extensions 13 so that the latter are uncovered.

Supported on the uppermost layer 16 of insulation is a pair of overlapping spring contacts 17 and 18, their free overlapping ends being suitably bent away from the switch base to permit such ends to have limited movement. The contacts are formed of flat spring metal and each contact, intermediate its ends, is eyeletted or otherwise secured at 19 to the insulating strip 16. Adjacent its extreme outer end, each spring contact is provided with an internally threaded sleeve 20 to receive the binding screws 21 for securing the terminals of the conducting wires (not shown) to the

switch. It is to be particularly noted that the eyelets 19 and screws 21 pass through the insulating strip 16 only and not through the strip 15, so that the latter acts as an absolute insulator and eliminates all danger of a possible short circuit between the upper metallic conducting parts and the lower metallic base 10.

Rotatably mounted in suitable openings in the standards 11 and 12 is a shaft 22, of full diameter for the greater portion of its length, but reduced at 22^a where it passes through the standard 12 and having its reduced end squared as at 22^b to receive and retain the switch arm 23 beyond the standard 12.

Carried by the shaft 22, intermediate its ends, is a cam disc 24 for operating the spring contacts 17—18. The disc 24 is provided with a flattened peripheral portion 25, which may be considered as the non-operative portion of the disc with respect to its action on the contacts 17—18. The disc is held in position on the shaft by being laterally confined between the inner faces of washers 26 and 27 interconnected by and preferably integral with a sleeve 28 firmly secured to the shaft 22. Coiled about the shaft 22 between the disc 24 and the standard 11 is a spring 29 one end of which is anchored to a lug 30 struck up from the metal of standard 11, and the other end of which is passed through openings in the disc 24 and washers 26 and 27 and is there secured by solder or in any other appropriate manner. Projecting from the outer face of the standard 12 is a headed stud or screw 31 serving as a stop for the arm 23 which, in effect, is rigid with the shaft 22.

As before stated, the switch is particularly adapted to control the operation of stop lights carried at the rear of automobiles, and when so used the switch arm 23 is connected by a cord or wire (not shown) to the brake lever of the vehicle. The arm 23 is provided with a plurality of spaced holes 32 through any of which one end of the cord may be passed, the position of the particular hole used for this purpose determining the throw of the arm under the action of the brake lever.

The contact springs 17—18, disc 24 and spring 29 are preferably enclosed by a dust excluding cover, which may consist of an arched insulating cap 33 and a similarly shaped metal hook 34. The cover as a whole

is easily applied to and removed from the switch and the members 33 and 34 are movable independently one of the other. The cap 33 has projecting ends 33^a which, when the cover is applied to the switch, overlie the eyelets 19 and form a support for the lower edge of the member 34. In this manner adequate insulation is provided between the hood 34 and other metallic conducting parts so as to prevent danger of short circuiting.

When the several parts of the switch are properly assembled, as shown in the drawing, the tension of spring 29 is such as to hold the arm 23 against the stop 31 (full line position of Fig. 4) and the flat portion 25 of disc 24 is parallel to springs 17-18 so that the latter are out of contact and the circuit is broken. It will be readily understood that the requisite tension may be imparted to spring 29 by removing stop 31, turning arm 23 as often as necessary, and then reinserting stop 31 against which arm 23 snaps. If the brake pedal of the vehicle, on which the switch is installed, be depressed in the act of stopping or slowing speed, pull will be exerted on the arm 23 causing rotation of shaft 22 and of disc 24. A very slight rotary movement of disc 24 will cause one end of the flat surface 25 to press against the uppermost spring 18 thereby moving the springs 17-18 into contact and causing illumination of the stop signal.

(not shown) which is electrically connected to the switch through one of the binding posts 21 the other being connected to the usual battery or other source of electric current carried by an automobile. When the brake pedal is fully depressed the arm 23 will assume the dotted line position shown in Fig. 4, with a part of the round periphery of the disc 24 pressing the springs 17-18 into contact and maintaining the stop signal illuminated. As soon as pressure is removed from the brake pedal the spring 29 will snap arm 23 back to its position of rest with the flat part 25 of disc 24 over springs 17-18 so that the latter will be out of contact and the signal will not be illuminated.

I claim:

An electric switch, comprising a supporting base and oppositely disposed standards, a shaft rotatably mounted in said standards, a sleeve on said shaft and parallel washers at the opposite ends of the sleeve, a disc carried by said sleeve and confined to its position by said washers, contact members on the supporting base in position to be acted on by the disc, and a spring coiled about said shaft, one end of said spring being anchored to one of the standards and the other end of the spring passing through said disc and washers.

In testimony whereof I have affixed my signature.

ABRAHAM W. ROSEN.
